CLOTHES-WASHING MACHINE

Charles D. Harrell, Knoxville, Tenn.

Application May 19, 1947, Serial No. 749,010

4 Claims. (Cl. 68—183)

1

This invention relates to improvements in washing machines, and more particularly to the type of washing machines in which clothes or fabrics are adapted to be washed by fluid action without mechanical agitation.

Most washing machines as used heretofore have required the action of an agitator for moving the clothes through the water with sufficient force and action to accomplish a washing of the clothes. This is objectionable because of the complexity of the structure required and the incidental cost involved, and also because the action of an agitator on the clothes tends to tear and damage the clothes whereby sheer fabrics, silks, nylons, etc., ordinarily are not washed in such machines.

Washing machines that utilize a fluid action to accomplish the circulation or movement of the clothes, as proposed heretofore, have not been satisfactory because of the lack of an effective washing action obtained thereby. This has been determined by the trial and testing of numerous types of fluid action devices in an effort to obtain a practical washing machine which functions according to fluid action.

An object of this invention is to improve the construction of washing machines, to provide a practical and effective washing action without moving parts or agitating means being operated in the tub of the machine, and yet securing an effective washing action.

Another object of the invention is to improve the manner of washing clothes by fluid circulation or pneumatic action imparted to the body of water in the tub of the machine in such relation thereto as to cause a continual turning over of the clothes within the water in an effective washing action.

Another object of the invention is to circulate air or other gaseous fluid into and through the tub to accomplish an effective washing action of the clothes, and in discharging the air therefrom, to prevent the carrying off of the soap and water with the air but to trap the latter so as to allow the effective release of the air without splashing of the water out of the tub.

Still another object of the invention is to provide a practical and inexpensive portable washing machine that may be manufactured at low cost and of light weight, and yet is effective for obtaining a washing action on the clothes contained therein, which machine may utilize as a power unit the action of a vacuum cleaner or other blower fan which will supply air to the machine under sufficient velocity to obtain an effective washing action.

2

These objects may be accomplished, according to one embodiment of the invention, by providing a tub having means for supplying air thereto, such as a connection for a blower fan mounted either beneath the tub or as an auxiliary attachment, in which latter event the fan may be provided by a vacuum cleaner. The air or other gaseous fluid used as the pneumatic power means is directed into the bottom of the tub through one or more nozzles provided therein in such relation to the wall of the tub as to create a circulation in the body of water and a continuous turning over of the ring of clothes in a toroidal manner which will accomplish an effective washing action.

The air or other gaseous fluid is directed into the bottom of the tub. Provision is made for releasing the air from the top thereof, but without splashing out of the water or soap that may be contained therein. This may be accomplished by baffle means connected with the top portion of the tub or the cover thereof which will break up soap bubbles to prevent these from being floated out with the air or the splashing of water from within the tub.

One embodiment of the invention is illustrated generally in the accompanying drawings in which:

Fig. 1 is a perspective view of the washing tub shown as connected with a vacuum cleaner power unit.

Fig. 2 is a top plan view of the tub.

Fig. 3 is a vertical sectional view therethrough.

Fig. 4 is a horizontal section through the tub on the line 4—4 of Fig. 3.

Fig. 5 is a detail cross section on the line 5—5 of Fig. 3.

Fig. 6 is a top plan view partly in section of the soap bubble cup.

Fig. 7 is a side elevation partly in section therethrough.

The embodiment of the machine as illustrated in the accompanying drawings is of a character adapted to form a portable washing machine of light weight and low cost, merely for purpose of illustration. It is recognized, however, that the machine may be embodied in a larger form for household use and may be of other sizes and shapes as found desirable.

In this form, the machine comprises an outer casing generally designated by the numeral 1 which is shown as mounted upon roller casters generally indicated at 2 for moving the machine about on the floor or other surface where the washing action may be desired.

Mounted within the casing 1 is a tub 3 adapted to contain the washing fluid, such as water and soap. This tub 3 is shown as round in shape, although it may be square or of other shape as desired. The tub 3 is shown as spaced from the casing 1 a sufficient distance to accommodate insulating means 4 therebetween as found desirable or necessary. The tub 3 may be mounted in any suitable manner within the casing 1 and in the form illustrated, a rim 5 connects the tub 10 with the casing at the upper end thereof.

The tub 3 is adapted to contain the washing fluid which may be hot water poured into the tub and provided with suitable soap or other chemicals as needed. Where the capacity of the machine is not very large, the heat will be retained a sufficient length of time to accomplish the washing action, but if necessary, a suitable heater may be provided especially in the later capacity machine for applying heat to the washing fluid during the washing action. This heater is indicated generally at 6 in Figs. 3 and 4 and is shown to be in the form of heating coils mounted beneath the bottom of the tub 3. These heating coils are shown as connected with a socket 7 at one side of the casing 1 adapted to receive an electric connection for energizing the coils to heat the washing fluid.

Provision is made for agitating the washing fluid by pneumatic means, to create a toroidal circulation of the fluid in the tub. In this form of the invention pneumatic action is accomplished by nozzles 8, two of which are shown spaced on opposite sides of the center of the tub. These nozzles should be spaced sufficiently from the inner wall of the tub to direct the force of air discharged therefrom upwardly in the water at a point which will act on the clothes to create a rolling over of the body of clothes in a toroidal action, while the body of clothes floats in the water substantially in a ring. This will cause a continual turning over of the ring of clothes in a manner that will accomplish an effective washing action.

The fluid nozzles 8 are shown as connected with a cross pipe 9 which in turn is connected with a supply pipe 10 that extends to a point externally of the machine, in the form illustrated, or to a suitable source of air supply, which may be mounted in the bottom of the casing if desired. In the form illustrated, the pipe 10 is shown as having a hose connection 11 extending therefrom to a vacuum cleaner motor unit generally indicated at 12. Such a motor unit utilizes a centrifugal blower fan which acts on one side thereof to suck in air and since it is an ordinary centrifugal blower fan, the air may be directed through the hose 11 and pipes 10 and 9 to the nozzles 8. Any suitable source of air supply may be used as found desirable, but it has been found from experience and tests of this invention that a source of compressed air is not very satisfactory because of the high pressure usually acting on the air, which is not required nor desired. A centrifugal fan of the character used in vacuum cleaner motor units has been found most satisfactory for ordinary sizes of washing machines and sufficient for accomplishing an effective washing action.

The machine is closed by a cover generally indicated at 13 which is shown as having a handle 14 thereon for manipulating the cover. The cover 13 is adapted to be secured tightly on the casing 1 by suitable catches such as toggle clamps indicated at 15.

The cover 13 is of dome shape and has air outlet orifice 16 in the top thereof for discharge of air from within the cover. A cover plate 17 extends transversely of the lower portion of the cover 13 over the top of the tub 3 to be seated thereon. It is preferred that the cover 13 be sealed substantially air or water-tight upon the top of the tub to prevent splashing of the water therefrom or accidental leakage which would be undesirable. I have found that this may be accomplished by the provision of a soft rubber gasket shown at 18 interposed between the rim 5 and the cover plate 17, which gasket will accomplish an effective sealing of the top of the tub when the cover is drawn down tightly thereon by the toggle clamps 15.

The air may be discharged through the cover plate 17 and the orifice 16 in the cover, but without discharging the soap from within the tub, by baffle means provided in the cover that will be effective for breaking up the soap bubbles to allow free escape of the air without carrying out the water and soap therewith.

In the form illustrated, this baffle means is shown as formed by cups attached to the cover plate 17. These cups are designated generally at 19 and 20 respectively, the cup 20 also serving as a trap.

The cup 19 is substantially of frusto-conical shape with a surrounding rim 21 on the lower end thereof while the upper end is closed. This cup 19 is inserted through an opening in the center of the cover plate 17 and retained in place therein in any suitable manner, as by friction fit, welding or the like if found necessary. The surrounding wall of the cup 19 is slit vertically at a plurality of points, as indicated at 22 in Fig. 6, and the lateral portions thereof bend inward to form indentations 23, which leave tangential openings into the cup through which the air may be discharged. The shape of these indentations is such that air may be discharged from within the tub but the edges of the openings will tend to break up any soap bubbles that would be carried out with the air.

The air discharged from the cup 19 is admitted to the interior of the cup 20 which is substantially annular in form, with an inturned neck 24, which forms a trap, as a further means for preventing the escape of fluid or soap with the air. The open end of the neck 24 is covered by a screen 25 extending thereover, as a further means of preventing the escape of the liquid or soap that may be carried into the trap 23.

The operation of the machine will be obvious from the foregoing description. Upon removal of the cover 13, the tub 3 is filled, preferably about three-fourths full with hot water, into which a small quantity of powdered soap usually is placed. Any suitable or desired washing fluid may be used as customary. The clothes then are placed in the water and ordinarily float therein in the form of a ring. Upon replacement of the cover 13 thereover and the sealing of this cover by the gasket 18 and clamps 15, the machine is ready for operation. Upon operation of the blower 12, air will be forced through the supply pipes 10 and 9 and discharged at the nozzles 8 in the bottom of the tub. These nozzles need not be of high velocity type, because it is preferred that only moderate pressure be applied to the air, which, with the placement of the nozzle or nozzles spaced laterally from the center of the tub and spaced inwardly from the periphery of the tub wall, will direct the air up-

5

wardly in the portion of the body of water and it will act on the outer rim of the ring of clothes, causing a continual turning over of the clothes in a toroidal action. Consequently, a plurality of nozzles is preferably spaced symmetrically with respect to the tub to act uniformly on the ring of clothes and causing the turning over or toroidal action which is effective for accomplishing the washing action.

The air will be discharged through the top of the tub, through the orifices 22-23 formed tangentially in the surrounding wall of the cup 19, into and through the trap 20, being discharged from the latter through the neck 24 and the orifice 16 out of the cover 13. The action of one or both of the cups 19 and 20 will be effective to permit the free escape of the air from the top of the tub without splashing out of liquid or soap or the carrying off of the soap with the air. It has been found from experience and from tests made with this machine that any soap bubbles accumulating in the top of the tub will be broken up and will not be carried out with the air. Any liquid that does go through the cup 19 with the air will be trapped in the cup 20 and will drain out through the orifices 22 back into the tub. If desirable, an additional filtering element may be provided in the cup 20 such as the placement of steel wool therein although this has not been found necessary with the machines subjected to tests.

The water may be removed from the tub 3 either by pouring it out when the tub is of small capacity or a separate drain faucet as indicated at 26 in Fig. 1 may be provided at one side of the casing adjacent the bottom of the tub and connected with the latter through a screened opening for draining off the washing fluid.

A rinsing action may be accomplished in like manner in plain water without soap. The air will accomplish an effective turning over of the clothes, moving them through the water substantially as described.

It has been found from tests made with this machine that it is effective for accomplishing a washing action of the clothes even without the use of an agitator or gears customarily required for most washing machines, and yet even the sheerest fabrics may be washed therein because there are no moving parts that would tear or damage the clothes. The gentle washing action is effective, as created by the air or pneumatic fluid acting in the water substantially as described.

This construction also simplifies the structure of the unit, enabling it to be manufactured and sold at low cost. It is also possible for the machine to be built of relatively small sizes so as to be readily portable, in which latter event it may be operated from the motor unit of a household vacuum cleaner usually available, or serve as an attachment for the vacuum cleaner, although it is not limited to that operating means. A centrifugal blower or other fan may be built into the machine beneath the tub, if desired.

While the invention has been illustrated and described in one embodiment, it is recognized that variations and changes may be made therein without departing from the invention except as specified in the claims.

I claim:

1. A washing machine comprising a tub adapted to contain a body of water to receive clothes therein for washing action, a cover mounted on the top of the tub and closing the same, means

6

for sealing the cover to the tub, said cover having a discharge opening therein for discharging air from within the tub, means located contiguous to the surrounding side wall of said tub for directing air under pressure upwardly in the lower portion of the tub at a point spaced laterally from the center of the tub to create a toroidal circulation in the water upward against the surrounding side wall and downward in the center, means mounted on the cover and surrounding the opening therein for preventing the escape of soap bubbles through the top opening, said means comprising a cup having circumferentially spaced openings in the surrounding side thereof of constricted size to permit the escape of air and to cause the breaking up of soap bubbles, and a second cup mounted on top of the cover surrounding the first-mentioned cup and forming a trap for receiving any liquid passing through the first-mentioned cup, said second-mentioned cup having a discharge opening with a screen cover thereover to permit the escape of air therethrough.

10 2. In a washing machine including a tub adapted to contain a body of soapy water therein to receive clothes for washing action, fluid supply means for creating pneumatic action in the water for causing a washing action on the clothes, said tub having a discharge opening in the top portion thereof, a closure for said top opening, and means for preventing the escape of soap bubbles through said closure, said last-mentioned means comprising a cup having circumferentially spaced openings in the surrounding sides thereof and deflecting vanes partially covering said opening to permit the escape of air and constructed to break up soap bubbles, said cup being mounted in said closure, and a second cup mounted on top of the closure and surrounding said first-mentioned cup and forming a trap for any liquid passing therethrough, said second cup having a discharge opening to permit the escape of air.

15 3. In a washing machine, a tub adapted to contain a washing fluid and to receive clothes therein for washing action, a cover for closing the top of the tub to confine the liquid therein and having an air discharge opening centrally located therein, a cup mounted in said opening, said cup having circumferentially spaced slits in the side wall thereof, the side wall adjacent one side of each of said slits being bent inwardly to form an opening with said slit which causes fluid to leave the cup in a direction tangent to the surrounding wall thereof, a second cup mounted on top of said lid and surrounding the first-mentioned cup, the side walls of said cups being in spaced relation to each other, the last-mentioned cup having the side walls inturned at one end to form a neck with an opening therein, a screen over the opening in said neck, a flat imperforate bottom in said tub, a pair of nozzles mounted in diametrically opposite sides of and extending through said bottom, said nozzles being located contiguous to the surrounding wall of said tub and in position to direct an upward jet of air through the fluid contiguous to said wall causing thereby a continual toroidal turning over of the clothes in the liquid, and means connected with said nozzles and mounted on the surrounding wall of said tub adapted to be connected to a supply of fluid for supplying fluid under pressure to said nozzles.

20 4. A washing machine comprising a casing having a tub therein adapted to contain a washing fluid and to receive clothes therein for washing

action, means for creating a circulation of the fluid in the clothes for causing said washing action, said tub having an open top, a cover detachably mounted on the open top, and means for discharging air from the interior of the tub to the atmosphere through the cover while confining soap in the tub, said means comprising a cup mounted in the cover and having peripheral openings in the surrounding sides thereof to permit the escape of air from the tub and to cause the breaking up of soap bubbles, a second cup mounted on top of the cover and superposed over the first mentioned cup and having a discharge opening for the air from the openings of the first mentioned cup, a screen over said last mentioned opening, and means in the cover for discharging the air from the second mentioned cup to the atmosphere.

CHARLES D. HARRELL.
